UNITED STATES PATENT OFFICE.

JOSEPH KING, OF TROY, NEW YORK.

SKATE.

No. 892,164.

Specification of Letters Patent.

Patented June 30, 1908.

Application filed July 30, 1907. Serial No. 386,233.

To all whom it may concern:

Be it known that I, JOSEPH KING, a citizen of the United States, resident of Troy, in the county of Rensselaer and State of New York, have made a certain new and useful Invention in Skates; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a side elevation of the skate. Fig. 2 is a section on the line 2—2, Fig. 3. Fig. 3 is a plan view of the skate. Fig. 4 is a section on the line 4—4, Fig. 2. Fig. 5 is a section on the line 5—5, Fig. 2. Fig. 6 includes detail plan views of the sections of the brace plate. Fig. 7 is a plan view of one of the bow springs. Fig. 8 is a detail perspective view of the top plate and its bolt.

The invention has relation to skates and more particularly to roller skates, and it consists in the novel construction and combinations of parts, as hereinafter set forth.

In the accompanying drawings, illustrating the invention, the letter *a*, designates the foot plates to which the bow springs *b*, have connection at the tops thereof. *c*, are tubular bearings for the roller shafts *d*, such bearings having intermediate cushioned block connections *e*, between the same and such springs, and longitudinal brace plates *f*, located below the bow springs. The foot plates are composed of two sections having overlapping reduced extensions *a'*, each provided with a central series of circular perforations *a''*. The brace plates *f*, are also composed of two sections having overlapping slotted inner end portions *f'*, one section thereof being provided with a double series of circular perforations *f''*, at each side of the slot and the other section having two pins *f''*, at each side of the slot for engagement with the perforations *f''*.

The cushioned blocks *e*, have each a grooved upper face *e'*, which receives the lower section of a bow spring, a transverse plate *h*, passing over this section of the spring and having clamp screw connections *h'*, with lateral extensions *e''*, of the block *e*. The blocks *e*, are of oblique spreading character from the tops thereof outward and downward, such tops being horizontal and the bottom faces having a right angular relation to

the inclined forward and rear faces of the block, such bottom faces being thus inclined slightly to the horizontal, as are the forward and rear faces inclined slightly to the vertical. These bottom faces of the blocks are also reversely inclined with respect to each other as is necessary owing to their right angular relation to the forward and rear faces. The bottom face of each block 60 has a groove *f''*, therein, in which lies a cushion *f''*, which is a little longer than the block and extends slightly beyond the same at each end. This rubber cushion bears at its bottom against an inclined carrier plate 70 extension *c'*, of the tubular roller shaft bearings such carrier plate having upward extending end projections *c''*, parallel to the sides of the block *e*. A securing bolt *g*, passes through a perforation *e''*, of the block 75 *e*, and through perforations *c''*, of the projections *c''*, the bolt having a right angular relation to the forward and rear faces of the block *e*, which is trapezoidal in longitudinal section. Each section of the longitudinal brace plate *f*, 80 has a downward outer end extension *f''*, parallel to the forward and rear sides of the block *e*, and also engaged by the securing bolt *g*. The upward projections *c''*, of the carrier plate thus do not bear directly against 85 the block *e*, but against the ends of the rubber cushion *f''*.

An adjusting bolt *h*, is carried by a top plate *i*, having a grooved lower face *i'*, embracing the inner reduced extensions of the 90 overlapping foot plate extensions such bolt passing downward through two aligned or registering perforations of such extensions and through the aligned slots of the brace plates *f*, a clamping thumb nut *j*, having a lock nut 95 washer *j'*, being provided at the lower end of such bolt. A bracing sleeve *k*, surrounds the bolt *h*, having broadened upper and lower horizontal faces *k'*, bearing against the foot plate sections at the top and the brace plate 100 sections at the bottom. Thus to adjust the length of the skate the thumb nut *j*, is unscrewed from the bolt and bolt and top plate to which it is attached removed. The foot plate sections together with the brace plate 105 sections being then slid upon each other for the desired adjustment the bolt and its top plate are replaced in position as beforestated.

Each bow spring is composed of upper and lower bow sections having flattened end extensions *b'*, overlying each other and having brace loop connections *b''*, having bolt con-

nection b^3 , therewith. The front or forward section of the foot plate has a transverse bar l , riveted thereto, such bar having an enlarged center portion l' , provided with a 5 grooved upper face l'' , in which fits the upper section of the bow spring. This center portion l' , has a downward forked extension l'' , which embraces the reduced unthreaded central portion of a transverse adjusting bolt m , 10 such bolt having reverse threaded engagement with downturned flanges n' , of the clamp plates n , such clamp plates having slots n^2 , engaging the transverse bar l , which is provided with a headed projection l^4 , at 15 each end, engaging the lower faces of said clamp plates. The rear section of the foot plate has also a transverse bar o , riveted thereto, such bar having an enlarged center portion o' , provided with a grooved upper 20 face o^2 , with which the upper section of the rear bow spring has engagement. The upper and lower bowspring sections are grooved or scored on their outer faces as shown at b^4 , to prevent slippage.

25 An ankle strap p , is riveted to the rear or heel section of the foot plate.

The rubber cushion block f^y , allows a considerable oscillation to either side of the foot plate and brace plate as also of the bow 30 springs and the intermediate block connections e , upon the bolts g , which is of great importance in turning corners.

The combination of the bow springs and rubber cushions in the relations described 35 aids greatly in relieving the parts of strain and provides an effective elastic bearing for the weight of the wearer.

This skate is of great strength, adapted to withstand much wear and is yet considerably 40 lighter than the usual roller skate.

Having described the invention, what I claim and desire to secure by Letters Patent is:

1. In a skate, a foot plate, tubular bearings, roller shafts therein, blocks having intermediate spring connections with said foot 45 plates and bolt connections with said tubular bearings, and cushions between said blocks and tubular bearings.

50 2. In a skate, a foot plate, tubular bearings, roller shafts therein, blocks having bolt connections with said tubular bearings and spring connections with said foot plate, cushions between said blocks and tubular 55 bearings, a longitudinal brace plate having connection with said blocks, and a vertical brace between said foot plate and longitudinal brace plate.

3. In a skate, a foot plate, tubular bearings, roller shafts therein, said tubular bearings having each a carrier plate extension 60 provided with end projections, blocks having connection with said foot plate and embraced by said end projections, said blocks having each a grooved lower face, cushions in the

grooves of said blocks between the same and the carrier plate extensions of the tubular bearings, a longitudinal brace plate having downward end extensions, and securing bolts passing through such downward end extensions 70 said end projections and said blocks.

4. In a skate, a foot plate composed of two extensible sections, bow springs connected at the tops thereof with said foot plate, blocks having connection with said bow springs at 75 the bottoms thereof, bearings for the roller shafts having connection with said blocks, roller shafts in said bearings, a longitudinal brace plate connecting said blocks and composed of two extensible sections, and a vertical 80 clamping and adjusting bolt connecting said foot and brace plates.

5. In a skate, a foot plate, bow springs connected at the tops thereof with said foot plate, blocks having connection with said bow springs at the bottoms thereof, bearings for the roller shafts having connection with said blocks, roller shafts in said bearings, a longitudinal 85 brace plate connecting said blocks, and a vertical brace between said foot plate and longitudinal brace plate.

6. In a skate, a foot plate, bow springs connected at the tops thereof with said foot plate, blocks having connection with said bow springs at the bottoms thereof, tubular 95 bearings having connection with said blocks, roller shafts in said bearings, cushions located between said tubular bearings and blocks, a longitudinal brace plate having connection with said blocks and a vertical 100 brace between said foot plate and longitudinal brace plate.

7. In a skate, a foot plate, bow springs connected at the tops thereof with said foot plate, blocks having connection with said bow springs at the bottoms thereof, tubular bearings, roller shafts therein, cushions between said tubular bearings and blocks, a longitudinal brace plate, and bolts connecting said blocks with said tubular bearings, 110 and longitudinal brace plate.

8. In a skate, a foot plate composed of two overlapping sections having each a series of perforations, tubular bearings, roller shafts therein, blocks having connection with said foot plate and having both connections with said tubular bearings, a longitudinal brace plate composed of two overlapping sections having slotted portions, a top plate having grooved lower face embracing the foot plate 115 sections and carrying a vertical bolt passing through aligned perforations of the foot plate sections and through the slots of the brace plate sections, and a bracing sleeve surrounding said bolt and bearing against said 120 foot plate and longitudinal brace plate.

9. In a skate, a foot plate composed of two overlapping sections having each a series of perforations, bow springs having connection at the tops thereof with said foot plate, 125

blocks having connection with said bow springs at the bottoms thereof, a longitudinal brace plate composed of two overlapping sections having slotted portions, a top plate 5 having a grooved lower face embracing the foot plate sections and carrying a vertical bolt passing through aligned perforations of the foot plate sections and through the slots of the brace plate sections, a bracing 10 sleeve surrounding said bolt and bearing at its ends against the foot plate and longitudinal brace plate, tubular bearings for the roller shafts, cushions between said tubular bearings and blocks, and bolts connecting said 15 blocks with said tubular bearings and longitudinal brace plate.

10. In a skate, a foot plate, bow springs connected at the tops thereof with said foot plate and composed of two bow sections having flattened overlapping end extensions, 20 loops embracing said flattened end extensions and having bolt connection therewith, blocks having connection with said bow springs at the bottoms thereof, tubular bearings for the roller shafts, and bolts connecting said blocks 25 and tubular bearings.

In testimony whereof I affix my signature, in presence of two witnesses.

JOSEPH KING.
